(57) **CLAIM**

The ornamental design for a bed topper, as shown and described.

DESCRIPTION

FIG. 1 is a perspective view of the bed topper;
FIG. 2 is a top plan view of the bed topper;
FIG. 3 is a left side elevation of the performance, the right side elevation view being identical thereto;
FIG. 4 is a front elevation view of the bed topper, the rear elevation view being identical thereto; and,
FIG. 5 is a bottom plan view of the bed topper.
The broken lines in FIG. 5 depict stitching.
